UNITED STATES PATENT OFFICE.

CARL C. THOMAS, OF MADISON, WISCONSIN.

METER.

1,218,717.

Specification of Letters Patent. Patented Mar. 13, 1917.

Application filed April 10, 1913. Serial No. 760,133.

To all whom it may concern:

Be it known that I, CARL C. THOMAS, a citizen of the United States, residing at Madison, in the county of Dane and State of Wisconsin, have invented new and useful Improvements in Meters, of which the following is a full, clear, concise, and exact description, reference being had to the accompanying drawing, forming a part of 10 this specification.

My invention relates to improvements in meters.

In my co-pending application, Serial No. 626,679, filed May 12, 1911, I have illustrated more or less diagrammatically, and have described the operation of a meter wherein the flow of steam, gas or vapors may be accurately determined and automatically recorded by the use of an electrically operated and controlled heater and a pair of resistance thermometers.

The present invention is directed toward the structural features and arrangement of such a meter, and has, among the more important objects which might be enumerated, the following:

To provide a meter wherein the losses and inaccuracies, due to different temperatures in different parts of the apparatus, are minimized, thereby insuring high efficiency and accuracy of operation.

To provide a meter in which the fluid flows substantially vertically through the heating and temperature indicating elements.

To provide for the ready removal of condensed moisture from the immediate vicinity of said elements.

To provide a construction wherein the important parts are readily accessible for inspection and repair.

In the accompanying drawings, I have illustrated what I consider to be the preferred embodiment of the invention. Other embodiments may be devised, however, which fall within the scope of the invention, and, accordingly, I do not limit myself to the construction illustrated.

Figure 1 is a central sectional elevation of the preferred construction.

Fig. 2 is a top plan view thereof, with the cover removed.

The meter is provided with a housing 1, having on one side a flanged extension 2 surrounding the inlet for the fluid whose flow is to be measured, and having a similar

flanged extension 3 on the opposite side, whereby said housing may be suitably bolted, or otherwise connected to pipes or conduits, the latter ordinarily being arranged horizontally. The housing is divided by a wall or partition 4, having an opening therein, preferably of circular form, which receives the barrel or cylindrical supporting element 5, the latter being provided with a suitable flange 6, whereby it may be secured in position by studs 7.

The direction of flow of fluid through the housing is indicated by the two arrows. Said gas entering at the left, as seen in Fig. 1, and flowing first diagonally downward and then vertically upward through the barrel 5, whence it flows diagonally downward to the right, and then through the outlet. The fluid, as it flows upwardly through the barrel 5, is heated by a suitable heater 8, which is preferably an electrical heater consisting of a screen or grid of resistance material through which current flows, thereby causing the resistor to dissipate heat. Said heater is located preferably about in line with the central part of the partition 4 and is arranged in a horizontal plane covering substantially the entire cross-sectional area of said barrel.

The temperature of the approaching gas is indicated by a suitable resistor or resistance thermometer 9, located below the heater 8. Said thermometer, in the preferred form, comprises a screen or grid of resistance wire disposed substantially uniformly over the cross-sectional area of the barrel. The resistance wire grid tends to assume the temperature of the fluid which flows therethrough, and, accordingly its resistance, which varies with its temperature, is an indication of the latter. The resistance is readily measured, as the screen is connected as part of an electric circuit, not disclosed herein, as it forms no part of the present invention. Furthermore, the details of the resistance thermometer and of the electric heater form no part of the present invention *per se*, and, accordingly, are not illustrated in all their detail.

The temperature of the gas, after it passes the electric heater, is measured by a second electric resistance thermometer 10, the latter being preferably a duplicate of the electric resistance thermometer 9, and suitably connected in circuit so as to indicate the rise in temperature of the gas, due

- to the heater. Without going into the details of the operation, which latter are set out fully in my co-pending application referred to above, it is sufficient for present purposes to understand that the current supplied to the electric heater 8 may be automatically regulated so as to maintain a constant temperature difference between the two resistance thermometers 9 and 10. If this is done, the electric energy consumed by the electric heater will be a measure of the quantity of the passing fluid irrespective of variations in the temperature or pressure thereof.
- 15 A suitable screen 11 is located at the lower end of the barrel 5, and a similar screen 12 is located at the upper end thereof. These screens insure greater uniformity in the flow of the fluid, and the lower screen serves to 20 catch foreign matter which may be conveyed therein, and to form a surface on which moisture may condense.
- It will be seen that the temperature of the entering gas is lower than that of the 25 gas as it leaves the housing, the difference being in some cases, about two degrees F. It is essential for the accurate operation of the meter that as little heat as possible be transferred, either to or from the body of 30 fluid between the thermometers, through the wall of the barrel 5. In order to insure that this heat transfer shall be a minimum, I have arranged said barrel within the housing in such a manner that the part of the 35 barrel below the heater is jacketed by the in-coming gas and thereby tends to maintain the same temperature as said in-coming gas; whereas, the part of the barrel above the heater is jacketed by the out-going 40 or heated gas. Hence the gas, both within and without the lower part of the barrel, is of substantially the same temperature, and likewise the gas within and without the upper part of the barrel is of substantially 45 the same temperature, although of a higher temperature than the gas below. Accordingly, there is no conduction of heat through the walls of the barrel either outwardly or inwardly. This insures 50 that there will be no change in the temperature of the flowing stream after passing the first thermometer and before reaching the heater, and after passing the heater and before reaching the second thermometer.
- 55 Thus, any losses or inaccuracies which might result from a heat transfer to or from the fluid between the thermometers are reduced to a minimum.
- The flow of fluid through the inner barrel 60 in a vertical direction has an important function in that, if the gas should cease to flow through the meter, due to some unexpected cause, the body of gas within the barrel and above the heater would be heated 65 to a much higher temperature than the gas
- below said heater. Accordingly, the difference in temperature between the lower thermometer and the upper thermometer would be considerably increased, thereby affecting the automatic control system in such a manner as to automatically reduce or cut off the flow of heating current through the heater. If the fluid flowed through a horizontal chamber within which the heater and thermometers were arranged in vertical planes, a cessation in the flow would result in the two resistance thermometers attaining eventually the same average resistance. In other words, the temperature difference that they represent, would decrease to zero, resulting in a tendency toward an indefinite increase in the heating current by the automatic control, to the great detriment of the equipment. To obviate this difficulty where a horizontally arranged chamber must be used, it is necessary to provide special auxiliary means for cutting off the heating current in an emergency such as suggested. Such special equipment forms the subject matter of a separate pending application. 80 In any case, if the heating current is not reduced, there is danger of destroying the heater and the thermometers, together with their associated parts.
- The present structure has a housing that 85 is adapted to be readily connected in the horizontal portion of a main, meters of this type being often employed to measure large quantities of steam, gas or vapors, the latter usually flowing through horizontal mains. 90 Of course, the inner barrel might be mounted directly within a vertical main. With a construction and arrangement of parts such as shown herein, the vertical flow of the fluid through the inner barrel is satisfactorily attained, even in conjunction with a horizontally arranged main or pipe. A further advantage of the vertical flow through the inner barrel is that the temperature of the entire cross-section of the 95 flowing stream, at any point, is more nearly uniform than if said stream were flowing horizontally. In other words, horizontal temperature stria and short circuits, i. e., local currents in the flow, are avoided. 100 Errors are also minimized, which might be caused by non-uniformity of resistance in the same corresponding areas of the two thermometers.
- It is important that any moisture which 105 is carried in the gas or other fluid be removed as far as possible before reaching the electrical elements located within the inner barrel. Said moisture tends to condense on the walls of the housing and, as 110 previously stated, is removed in part by said screen 11. The moisture, therefore, drains naturally to the lowest part of the housing and may be removed through a suitable outlet 13, arranged preferably in 115

a removable cover 14. An additional cover or top cover 15 is provided, the latter giving ready access to the inner barrel 5, which latter may, therefore, be removed, if necessary or the various electrical appliances mounted therein may be removed independently thereof or may be inspected whenever desired.

The electrical connections with the external circuits are made within a suitable inclosure or outlet box 16, located preferably at the side of the housing. The circuit conductors and the terminals are not shown as they are not material to the present disclosure.

It is to be understood, of course, that, as previously stated, the invention is not limited to the details of construction or relative arrangement of parts disclosed herein, except where limitations are imposed in the appended claims. As far as some of the phases of the invention are concerned, it is immaterial whether the heater and the thermometers be of a construction essentially electrical or otherwise, although the electrical equipment has certain advantages. I desire, therefore, to cover, as falling within the scope of the invention, whatever other elements may be substituted, capable of performing the same general functions, and whatever other general forms may be devised, wherever such modifications fall within the scope of said claims.

Having thus described my invention, what I claim as new and desire to secure by Letters Patent of the United States is:

1. In a fluid meter, means for heating the fluid as it flows therethrough, and means causing the heated and unheated fluid to jacket the fluid being heated.
2. In a fluid meter, means for heating the fluid as it flows therethrough, a pair of temperature responsive devices one subjected to said fluid before and the other after heating, and means causing the entering fluid and the out-going fluid to jacket the fluid between said temperature responsive devices.
3. In a fluid meter, means for heating the fluid and means for directing said fluid past said heater and preventing a deviation in the temperature of the fluid about to be heated from the temperature of the fluid entering the meter.
4. In a fluid meter, means for heating the fluid and means for directing said fluid past said heater and preventing a deviation in the temperature of the fluid immediately after heating.
5. In a fluid meter, means for heating the fluid as it flows therethrough, and means causing said fluid to be jacketed by fluid at its own temperature just prior to being heated and to be jacketed also just subse-

quently to being heated, by fluid at its increased temperature.

6. In a fluid meter, means for heating the fluid, means for directing said fluid past said heater, and means for preventing a transfer of heat through the said directing means adjacent to the heater.

7. In a fluid meter, means for heating the fluid, a resistance thermometer arranged on each side of said heating means, means for directing said fluid past said heater and said resistance thermometers, and means for preventing a transfer of heat through the said directing means between the two points where the thermometers are located.

8. A fluid meter comprising a housing, a vertically arranged conduit therein, an inner wall dividing said conduit into an upper and a lower chamber, said conduit passing through said wall and being supported thereby, a heater arranged within said conduit, and a pair of temperature responsive devices, also arranged within said conduit, one on each side of said heater, the fluid, whose rate of flow is to be measured, flowing through said conduit and surrounding the same both above and below said wall, whereby the lower end of said conduit is jacketed by the cooler in-coming fluid, and the upper end of said conduit is jacketed by the out-going heated fluid.

9. In a fluid meter wherein the rate of flow is determined by a change of temperature in the flowing fluid, a pair of heat responsive devices arranged one over the other, whereby the tendency of the heated fluid to rise affects said temperature responsive devices and causes a deviation from the normal operation to prevent excessive heating if said fluid lessens its normal flow.

10. In a fluid meter, a housing having outlet and inlet ports in substantially horizontal alignment, means for causing the fluid to flow through said housing in a substantially vertical direction, an electric heater in said housing, and a pair of resistance thermometers arranged one above and one below said heater whereby the upwardly flowing fluid will be heated and the increase of temperature indicated by said resistance thermometers, and whereby when the flow of fluid abnormally decreases or ceases, said resistance thermometers will indicate an abnormal temperature difference between the two and thereby automatically provide an unbalanced condition available for controlling purposes.

11. A fluid meter having a housing arranged to cause the fluid to flow vertically therethrough, means for heating the flowing fluid, means for measuring the temperature of the fluid before and after heating and means for insuring that the temperature of the fluid passing the heating and tem-

perature measuring means is substantially uniform at any given cross section of the flowing stream.

12. In a fluid meter, a housing having outlet and inlet ports in substantially horizontal alinement, means in said housing for causing the fluid to flow vertically therethrough and electrical heating and temperature responsive appliances arranged in said housing in vertical alinement for the purpose specified.

13. In a fluid meter, a housing, a vertical conduit arranged therein, a heater arranged horizontally within said conduit and disposed across the same, and a pair of resistance thermometers arranged one above and one below said heater and each disposed across said conduit, whereby fluid flowing upwardly through said conduit will be heated and the increase of temperature indicated by said resistance thermometers, and whereby an abnormal decrease or cessation of the flow of said fluid will result in said resistance thermometers indicating an abnormal temperature difference between the two.

14. In a fluid meter, a housing having inlet and outlet ports arranged substantially in horizontal alinement, means within said housing for directing the flow of fluid in a vertical direction, and means for heating said fluid during its vertical flow.

15. In a fluid meter, a housing, a conduit

spaced from the outer walls thereof and surrounded by the fluid whose flow is being measured, and a partition about the middle of said conduit to separate the heated from the unheated fluid whereby the condensation of any vapor carried by said fluid is substantially prevented during its passage through said conduit.

16. A meter comprising a housing having openings at opposite sides thereof, and having an outlet at the lowest point of said housing for draining moisture which may collect therein, a partition within said housing serving to divide the same into an upper and a lower chamber with each of which one of said openings communicates, a vertically arranged barrel supported centrally within said partition, an electric heater arranged centrally within said barrel, an electric resistance thermometer arranged on each side of said heater within said barrel, a screen arranged near each end of said barrel, and the upper part of said housing consisting of a removable cover whereby access may be had to said barrel and associated parts.

In witness whereof, I have hereunto subscribed my name in the presence of two witnesses.

CARL C. THOMAS.
